BRANDING SHEET

William P. Donald, Cleveland, Ohio, assignor to
Wean Equipment Corporation, Euclid, Ohio, a
corporation of Ohio

Application March 22, 1950, Serial No. 151,184

4 Claims. (Cl. 101—235)

1

This invention relates to branding sheets. It has to do particularly with apparatus for branding sheets advancing sequentially to a branding station.

I have developed the invention in connection with the branding of sheets delivered sequentially from a continuous strip galvanizing line. In such a line the strip, ordinarily steel strip, is continuously galvanized and after being galvanized is cut into sheets which are delivered or advanced one after another. It is desirable for the manufacturer to apply his brand or trademark to each individual sheet. The brand should be applied uniformly to all sheets, i. e., at the same position, with the same orientation and with the same force so that the brands will be uniform in all respects. It has been customary to brand sheets by hand, that is, by having a workman with a branding stamp press the stamp against each sheet. Such a procedure is costly because of the labor involved and also because it introduces a time bottleneck in the operation and may result in otherwise unnecessary slowdown. Moreover, the human equation cannot be eliminated, the result being that the brands are not uniformly applied to all sheets.

By use of my invention I can brand sheets rapidly, efficiently and uniformly. The branding is done mechanically and the human equation is eliminated. The brand is applied to all sheets uniformly as to position, orientation and force of impression. The sheets are branded as they advance sequentially after having been sheared from the continuous galvanized strip. While, as will appear in relation to one feature of my invention, I preferably utilize the light reflecting character of galvanized sheets in the actuation of the brander, the invention is not limited to the branding of galvanized sheets. It is applicable in all respects to the branding of any sheets having substantial light reflecting characteristics. In certain aspects the invention is applicable to the branding of any sheets whether or not they have light reflecting characteristics. I use the term "sheet" as a word of broad definition and not of limitation; it is intended to comprehend any articles having surfaces adapted to receive a brand, the articles having in that respect the characteristics of sheets. I also use the term "brand" as a term of broad definition and not of limitation; it comprehends any marking, trade-mark or otherwise, which it may be desired to apply to the sheets. Purely for purposes of explanation and illustration I shall describe the invention in con-

2

nection with its embodiment in apparatus for sequentially branding galvanized sheets moving to a branding station one after the other.

In a modern continuous steel strip galvanizing line the strip moves continuously through a galvanizing station where it is galvanized, and the strip is continuously delivered from the galvanizing station and cut into sheets. The sheets may be advanced sequentially to a branding station where they are acted on by my branding apparatus. I preferably employ a branding device positioned to brand each sheet as the sheets advance one after the other, the branding preferably being accomplished while the sheets are moving and without appreciably slowing them down or in any way affecting their advance. I preferably employ control means for the branding device which is actuated by each sheet as it approaches the branding station. I preferably provide a power source and the control means preferably acts to connect the branding device to the power source to effect the branding of a sheet. The mechanism is desirably such that after a single cycle of operation to apply one brand to each sheet it returns to its initial condition ready for the succeeding cycle. The connection between the power source and the branding device may be a single revolution driver such as a single revolution clutch. The branding device may be a rotary branding device positioned to brand the sheet at the branding station upon being driven through one revolution.

The power source may be continuously operated independently of the sheets although I find it expedient to employ as a power source a wheel which is engaged by the sheets as they move along, the sheets causing the wheel to turn. While the sheets may be advanced on any suitable guideway or conveyor I find it desirable for various reasons to employ a moving conveyor upon which the sheets are disposed, as, for example, an endless belt conveyor. When such a conveyor is employed the wheel which serves as the power source is driven continuously. When it is in contact with a sheet lying on the conveyor it is driven by the sheet. It contacts the conveyor between the trailing edge of each sheet and the leading edge of the succeeding sheet. The power wheel and the rotary branding device may be mounted side by side in coaxial relationship. The single revolution drive is mounted in relation to the power wheel or driving roll and the rotary branding device or branding roll so as to be actuatable to connect the branding roll to the driving roll to cause the branding roll to turn through

a single revolution and then stop. The single revolution driver may comprise a single revolution clutch of any suitable construction, such, for example, as the clutch disclosed in Patent No. 2,140,737. Since the single revolution clutch is a known device and does not constitute my invention it is not necessary to illustrate it or describe it in detail. I preferably provide means, such, for example, as a pawl, adapted to coact with a member of the single revolution clutch, which member may advantageously be in the form of a rotary cam with a single step in its periphery as disclosed in said Patent No. 2,140,737, the pawl normally engaging the cam step to maintain the clutch inoperative but being retractable to allow the clutch to operate to drive the branding roll through a single revolution. The pawl is preferably normally maintained in operative position against the cam step by spring or equivalent means and is adapted to be withdrawn against the action of such means to clear the cam step and thus permit initiation of operation of the clutch by means actuatable by the control means, as, for example, a solenoid. The solenoid acts almost instantaneously and immediately after it has withdrawn the pawl the spring or other biasing means acting on the pawl returns the pawl into engagement with the cam so that it lies in the path of the cam step to stop the cam and render the clutch inoperative at the end of a single revolution.

As above indicated I find it expedient when branding sheets having light reflecting surfaces, such as galvanized sheets, to employ the light reflecting character of the sheets to operate the control mechanism. I desirably provide a light source casting light on the path of the sheets and light sensitive means such as a photoelectric cell positioned to receive light from the light source reflected by a sheet. When no sheet is in the path of the light beam the light is not reflected to the light sensitive means. This result may be accomplished either through providing a slit in the conveyor in the path of the light beam or by making the conveyor of light absorbing as distinguished from light reflecting character. Thus the control mechanism is actuated when the leading edge of each sheet reflects light from the light source to the light sensitive means, the latter operating the connection between the branding device and the power source to cause operation of the branding device to brand the sheet. The mechanism is preferably such, as explained above, that the brander operates for only one cycle per sheet; the light sensitive means will not reactivate the control mechanism until the trailing edge of the sheet has passed the light beam and the leading edge of the succeeding sheet has intercepted the light beam.

I provide a time delay device in the control circuit, such device being adjustable to bring about connection of the branding device to the power source after a predetermined time interval following interception of the light beam by the leading edge of a sheet. By adjustment of the time delay device the position of the brand relatively to the leading edge of the sheet is determined. The time delay device is adjusted in relation to the speed of movement of the sheets so that the brand will be applied the desired distance from the leading edge of the sheet. Uniform brand positioning may be accomplished when the speed of movement of the sheets is changed by correspondingly changing the setting of the time delay device.

The branding device is preferably mounted so that it may be moved transversely of the path of the sheets to position the brand at any desired transverse location. Means are also preferably provided for moving the branding device to inoperative out-of-the-way position when it is not to be used.

Other details, objects and advantages of the invention will become apparent as the following 10 description of a present preferred embodiment thereof proceeds.

In the accompanying drawings I have shown a present preferred embodiment of the invention in which:

15 Figure 1 is a plan view of sheet branding apparatus;

Figure 2 is a side elevational view of the sheet branding apparatus shown in Figure 1;

Figure 3 is an end elevational view with a portion cut away of the sheet branding apparatus 20 shown in Figures 1 and 2;

Figure 4 is an enlarged detail view partly in elevation and partly in vertical cross section on the line IV—IV of Figure 5;

25 Figure 5 is a further enlarged detail view partly in elevation and partly in vertical cross section on the line V—V of Figure 4; and

Figure 6 is a circuit diagram showing the electrical connections through which the apparatus 30 operates.

Referring now more particularly to the drawings, there is shown an endless belt conveyor 2 whose upper reach moves from right to left viewing Figures 1 and 2. The conveyor 2 is driven by a motor 3. Sheets to be branded are delivered to the branding station, designated generally by B in Figure 2, on the conveyor 2. The sheets may be fed to the conveyor in any suitable manner, either continuously from the strip galvanizing line or otherwise. The sheets lie atop the upper reach of the conveyor and are slightly spaced apart, i. e., the leading edge of each sheet is some distance behind the trailing edge of the sheet in front. One virtue of my brander is that it functions to brand each sheet in exactly the same way regardless of the distance between sheets on the conveyor and regardless of whether or not the sheets are equally spaced.

50 The sheets being branded will be considered as sheets having light reflecting surfaces, such, for example, as galvanized sheets. In the control of the brander I employ a light source disposed to cast light on the path of the advancing sheets and light sensitive means positioned to receive light reflected from the sheets. The conveyor 2 is constructed so that it does not reflect light from the light source to the light sensitive means between the time when the trailing edge of one sheet has passed the light beam and the time when the leading edge of the succeeding sheet reaches the light beam. Either the conveyor may have a slit through which the light beam passes between sheets or the material of the conveyor may be of light absorbing as distinguished from light reflecting character. In either event light from the light source is reflected into the light sensitive means by the sheets when they intercept the light beam while no light, or insufficient light to operate the light sensitive means, is reflected into the light sensitive means between sheets.

55 At the branding station B is a supporting frame 4 comprising opposed standards extending generally vertically on opposite sides of the con-

70

veyor 2. At a substantial distance above the conveyor 2 two cross bars 5 extend generally horizontally between the standards. The cross bars 5 form the top of the supporting frame and directly support the brander.

The brander comprises a brander frame 6 including sleeves 7 receiving the bars 5 and slideable therealong. There are two sleeves 7 receiving and slideable along each of the bars 5. The entire brander carried by the brander frame 6 is adapted to be moved transversely of the conveyor 2 along the horizontal bars 5. A screw 8 is journaled in the tops of the standards 4 and is adapted to be turned by a handwheel 9. The brander frame 6 fixedly carries a nut 10 into which the screw 8 is threaded. Thus upon turning of the handwheel 9 and consequent rotation of the screw 8 the brander will be moved longitudinally of the bars 5. The transverse position of the brander relatively to the conveyor 2 and hence relatively to the sheets on the conveyor is adjusted by operation of the screw 8.

The brander frame 6 carries a transverse shaft 11 which in turn carries for swinging movement in a vertical plane parallel to the length of the conveyor 2 a bracket 12. A pivoted pressure cylinder 13 is pivoted to the brander frame 6 at 14 and contains a piston having a piston rod 15 pivoted to the bracket 12 at 16. By operation of the piston in the cylinder 13 the bracket 12 swings about the axis of the shaft 11 between a lower operative position as shown in the drawings and an upper inoperative position in which the brander is withdrawn so that it cannot act on sheets advancing on the conveyor 2.

Journaled in the bracket 12 is a shaft 17 to which is keyed a branding wheel 18. The branding wheel 18 carries at a portion of its periphery a branding stamp adapted when the branding wheel 18 rotates while in operative position to brand a sheet moving past the branding station B on the conveyor 2. As a power source for operating the brander I provide a rubber tired wheel 19 mounted for free rotation on the shaft 17. I provide a single revolution clutch operable between the driving wheel 19 and the branding wheel 18. The driving section 20 of the single revolution clutch is carried by the driving wheel 19. The driven section 21 of the single revolution clutch is keyed to the shaft 17 and hence always rotates with the branding roll 18. The sections 20 and 21 of the single revolution clutch are normally disengaged from each other so that the wheel 19 may ride upon the conveyor 2 and the sheets disposed thereupon (one of the sheets is designated 22 in the drawings) whereby the wheel 19 is in effect continuously driven. It turns freely on the shaft 17 which does not rotate except during operation of the branding wheel 18.

There is provided a pawl 23 normally actuated by a tension coil spring 23a into engagement with a rotary cam 23b carried by the driven section 21 of the single revolution clutch, the cam 23b having a single cam step 23c in the path of which the pawl 23 lies during rotation of the cam. When the pawl 23 lies against the cam step 23c the single revolution clutch is maintained inoperative but when the pawl is momentarily withdrawn the single revolution clutch operates to turn the branding wheel 18 with the driving wheel 19 through a single revolution. During that revolution the spring 23a returns the pawl 23 into contact with the cam 23b so

that at the end of the revolution the cam step 23c engages the pawl and stops. Since, as explained above, the single revolution clutch is a well known device its detailed mechanism need not be explained. I have found that a friction drag brake (not shown) may, if desired, be applied to advantage to the shaft 17. There may at times be a tendency of the branding wheel 18 which is keyed to the shaft 17 to oscillate when turning of the branding wheel is stopped by the single revolution clutch; such tendency is counteracted or the oscillation damped by the friction drag brake.

The light source above referred to is designated 24 and is carried by the brander frame 6. It casts a beam of light generally downwardly but at an angle to the vertical so that the beam of light is intercepted by sheets moving along the conveyor 2. The light sensitive means above referred to is also carried by the brander frame 6 and is designated 25. The light sensitive means 25 may be a photoelectric cell or so-called "electric eye." It receives light from the light source 24 reflected by each sheet as it intercepts the beam of light.

The pawl 23 is actuated to inoperative position against the action of its spring 23a by a solenoid 26 which is energized by a circuit which is closed by the electric eye 25 when light is reflected to it from the light source 24. A time delay device which may be of conventional construction and which may be adjusted to vary the extent of time delay is interposed between the electric eye 25 and the solenoid 26 so that the solenoid 26 is operated at a predetermined time after operation of the electric eye. This means that the pawl 23 is rendered inoperative at a predetermined time after operation of the electric eye and hence that the time of commencement of rotation of the branding wheel 18 may be accurately determined. In this way the exact positioning of the brand at a desired distance from the leading edge of the sheet may be determined. Ordinarily the conveyor 2 operates at constant speed but if the speed of the conveyor 2 is changed the adjustment of the time delay device should be correspondingly changed to insure continuing of application of the brand at the same relative spot on each sheet. The circuit also is such that the solenoid 26 is operated only once for each sheet and cannot be operated again until the trailing edge of the sheet has passed beyond the light beam and the leading edge of the succeeding sheet has intercepted the light beam.

The branding stamp is positioned on the branding wheel 18 so that it is pressed against the surface of the sheet upon rotation of the branding wheel. An inking roller 27 is provided for inking the branding stamp upon each operation of the branding wheel.

When the brander is raised to inoperative position by admitting fluid to the right of the piston in the cylinder 13 viewing Figures 2 and 4 a lug 28 on the bracket 12 opens a switch 29 which renders inoperative the electrical circuit so that the brander when raised does not function even though sheets may continue to be advanced on the conveyor 2. If the branding wheel should chatter during operation because of surface irregularities fluid pressure can be admitted to the left of the piston in the cylinder 13 viewing Figures 2 and 4 to increase the pressure of the branding wheel 18 on the sheet surface to which the brand is to be applied. Or-

dinarily the mass of the brander is sufficient to insure adequate pressure of the branding stamp but it can be enhanced if desired in the manner just explained.

I shall describe the operation of the brander in branding a sheet advancing to the branding station B on the conveyor 2. Prior to interception by the leading portion of the sheet of the light beam from the light source 24 the light beam is not reflected into the electric eye 25. As the leading edge of a sheet intercepts the light beam it reflects light into the electric eye 25 resulting in closing through the time delay device of the circuit energizing the solenoid 26 for rendering inoperative the pawl 23. Since the wheel 19 is turning continuously through contact with the sheets and the conveyor shaft 17 and the branding wheel 18 are rotatively connected with the wheel 19 by the single revolution clutch and turn with the wheel 19 to apply the brand to the sheet. At the end of a single revolution the pawl stops the turning of the branding wheel 18 by disengaging the clutch as above described; this occurs after the branding wheel has applied a single brand to the sheet. The continued reflecting of light from the light source 24 into the electric eye 25 as the trailing portion of the sheet passes through the light beam has no effect on the brander. After the trailing portion of the sheet has moved beyond the light beam light is no longer reflected into the electric eye 25 and the brander is ready for repetition of the cycle as soon as the leading edge of the succeeding sheet intercepts the light beam to reflect light into the electric eye 25.

Referring now to the circuit diagram Figure 6, current is supplied through line terminals 29 and 40 from any suitable source of power; for example, the current may be 110 volt, 60 cycle, alternating current. Manually operable switch elements 41 and fuses 42 may be provided in accordance with the usual practice. The limit switch 29 above referred to is shown in Figure 6 and when the mechanism is to be used the switch elements 41 and the limit switch 29 must be closed.

When light from the light source 24 is reflected into the electric eye 25 the latter closes contacts 30, energizing coil 31 which after a predetermined delay depending upon its setting closes contacts 32. Closing of contacts 32 energizes coil 33 which closes contacts 34 and energizes solenoid 26. Energizing of solenoid 26 retracts the pawl 23 as above explained. The result of retraction of the pawl is that the single revolution clutch operates, turning the branding wheel 18 through a single revolution to apply a brand to a sheet.

To make certain that the solenoid 26 will deenergize before the branding roll 18 has completed its single revolution cycle timing relay 36 deenergizes coil 33 during the single revolution of the branding roll thus insuring return of the pawl 23 under the action of its spring 23a to operative position to engage the cam step 23c at the end of one revolution of the cam 23b.

To prevent energizing of the solenoid 26 more than once for each closing of the contacts 30 there are provided normally closed contacts 35 which are opened after the coil 31 has been energized for a predetermined time, resulting in deenergizing of coil 33. Contacts 35 will not close until coil 31 is deenergized by opening of contacts 30 after passage of a sheet. When a

sheet has passed contacts 30 open and in turn contacts 32 open, thus resetting the system for the next cycle.

There is provided a selector switch 37 which in the position shown in Figure 6 provides for automatic operation as above described. If the selector switch 37 is thrown to its lower position viewing Figure 6 the mechanism will not operate automatically but may be operated manually through a push button switch 38.

While I have shown and described a present preferred embodiment of the invention it is to be distinctly understood that the invention is not limited thereto but may be otherwise variously embodied within the scope of the following claims.

I claim:

1. A sheet brander comprising means along which sheets are advanced, said means having a surface over which sheets being advanced are adapted to be disposed which is relatively light absorbing, a light shining on said surface, a turnable branding device and means including light sensitive means receiving light reflected from a sheet disposed over said surface turning the branding device to brand the sheet.

2. A sheet brander comprising means along which sheets are advanced, said means having a surface over which sheets being advanced are adapted to be disposed which is relatively light absorbing, a light source disposed to cast light on said surface, a branding device and means including light sensitive means receiving light from said source reflected from an advancing sheet operating the branding device to move generally with the sheet to brand the sheet while the sheet continues its advance along said means.

3. A sheet brander comprising a power source, a rotary branding device positioned to brand advancing sheets when the branding device is operated, a light source disposed to cast light on the path of the advancing sheets, light sensitive means positioned to receive light reflected from the sheets and connecting means actuated by the light sensitive means connecting the power source and the branding device so that the power source rotates the branding device to brand a sheet.

4. A sheet brander comprising a wheel engaging advancing sheet to be turned thereby, a branding wheel positioned to brand the advancing sheets when the branding wheel is turned, a light source disposed to cast light on the path of the advancing sheets, light sensitive means positioned to receive light reflected from the sheets and connecting means including a single revolution driver actuated by the light sensitive means connecting the first mentioned wheel and the branding wheel so that the branding wheel turns with the first mentioned wheel through a single revolution to brand a sheet.

WILLIAM P. DONALD.
